A. F. KELLY

VEHICLE WHEEL

Filed Dec. 2, 1920

Inventor
ADELBERT F. KELLY

By Paul & Paul
His Attorneys.

UNITED STATES PATENT OFFICE.

ADELBERT F. KELLY, OF SPOKANE, WASHINGTON.

VEHICLE WHEEL.

Application filed December 2, 1920. Serial No. 427,826.

To all whom it may concern:

Be it known that I, ADELBERT F. KELLY, a citizen of the United States, resident of Spokane, county of Spokane, State of Washington, have invented certain new and useful Improvements in Vehicle Wheels, of which the following is a specification.

This invention relates to improvements in spring-spoke wheels and has particular reference to the hubs used in motor vehicle wheels employed in conjunction with such resilient spokes. These improvements are generally directed to simplification of construction, reduction of weight and number 15 of parts and increased strength and durability. This invention is a modification and improvement of the general type of spring-spoke wheel forming the subject-matter of a prior patent granted to the inventor hereof, No. 1,328,244, issued January 13, 1920.

The object of this invention is to provide an improved spring-spoke wheel.

Other objects of the invention will more fully appear from the following description 25 and the accompanying drawings and will be pointed out in the annexed claims.

In the accompanying drawings there has been disclosed a structure designed to carry out the objects of the invention, but it is to 30 be understood that the invention is not confined to the exact features shown as various changes may be made within the scope of the claims which follow.

In the drawings:

Figure 1 is a fragmentary view in side elevation of the hub plate with the cover plate partially broken away;

Figure 2 is a section on the line 2-2 of Figure 1;

Figure 3 is a section on the line 3-3 of Figure 1;

Figure 4 is a fragmentary perspective of the assembled hub and spokes;

Figure 5 is a perspective of the inner portion of a complementary pair of spokes;

Figure 6 is a view in side elevation of a portion of the assembled wheel.

In this selected embodiment of the invention, there is provided a wheel hub having 50 a body member such as a metallic hub plate 7. This hub plate is adapted to have secured thereto a metallic cover plate 8 which is preferably in the form of a flat ring. The plate 8 is held to the hub plate by means of 55 a plurality of annularly disposed bolts 11

passed through holes in the two plates and secured by the nuts 12.

The hub plate is provided with an annular thickened portion adjacent its central axle opening 9. This thickened portion is 60 preferably formed by building up the metal substantially in the form of an inner annular shoulder 13 which axially projects from the relatively thin hub plate proper. A plurality of annularly disposed recesses are 65 provided in this shoulder 13 and in each one of these recesses is adapted retentively to be seated the terminal hub portion of the spoke member. In the form here disclosed these spoke members are complementary pairs of 70 opposingly bowed spring-spokes 14 and 15, each complementary pair being provided with hub portions 16 and 17 which are normally in adjacent parallelism. The inner terminal portions of each pair are prefer- 75 ably shaped to provide a single solid head of such configuration that the head may be positioned within and be retentively seated in a recess. As here shown, the spoke terminals are formed to provide an interlocked 80 head. One terminal portion 18 of each complementary spoke pair is shaped to provide a solid head while the terminal portion 19 of its complement is shaped tightly to embrace such head and the single unitary head 85 thus formed is adapted to be retentively seated in one of said recesses provided on the built-up shoulder 13 of the hub plate. Thus, when the cover plate 8 is secured in position, the spoke heads are held against 90 any axial displacement.

Means are also provided on the hub plate to maintain the hub portions of the spokes in their normal annularly spaced paired relation. A relatively constricted spoke channel, outwardly extending from each recess, is provided on the hub plate 7. The walls of each channel are formed by the portions 21 of ribs preferably integral with the hub plate 7 and axially projecting therefrom. 100 These rib portions 21 outwardly extend in opposed spaced pairs from each recess. The hub portions 16 and 17 of each complementary spoke pair are positioned and outwardly extend from a recess through a 105 channel.

In this improved hub, resilient means are provided adjacent the hub periphery yielding to resist distortion of the spoke members. Herein, such resilient means are dis- 110

- closed as rubber blocks 22 carried in compartments provided by the hub plate 7. The ribs outwardly extending beyond the portions 21 are offset to form the compartment walls 23. The rubber blocks 22 are positioned in each compartment on each side of the hub portions of the spoke pair outwardly extending therethrough, the spokes being preferably of such shape that the normally adjacent hub portions extend slightly beyond the blocks 22. Hence, upon exertion of the compressive stress upon the lowermost spokes of the wheel, the attendant separative distortion of the spokes at the hub portions will yieldingly be resisted by the blocks. Furthermore, it may be pointed out that the portions 24 of the hub plate 7 and the cover plate 8, which are adjacent the hub portions of the spokes, are outwardly tapered or reduced in thickness as shown in Figure 3. This recession of the opposed faces of the hub and cover plates decreases liability to frictional wear of the hub portions of the spokes against these plate faces.
- 25 A closure of the peripheral spaces between adjacent compartment blocks is afforded by means of a plurality of axially projecting members annularly disposed adjacent the periphery of one of the plates and 30 adapted to abut against or to be engaged by the inner face of the other plate. In this preferred embodiment of the invention, such members 25 are formed integrally with the hub plate 7 and axially project as shown in Figure 2, to abut against the inner face of the cover plate 8 when the plate is in assembled position. These annularly segmented members 25 are preferably of such circumferential dimension that each end 35 projects slightly beyond the adjacent compartment wall and into the compartment, the rubber blocks 22 being cut away or shaped accordingly.
- The metal around the bolt holes 26 of 40 the hub plate is preferably slightly built-up to provide a boss 27 for the holes 26 and to strengthen somewhat the offset portions 23 of the ribs forming the compartments containing the resilient blocks 22.
- 45 It is to be understood that any suitable form of hub proper for the usual axle may be employed. The hub proper is here shown generally as an axially disposed sleeve 28 integral with the hub plate.
- 50 Having thus described my invention what I claim as new and desire to secure by Letters Patent is:
- 55 1. A wheel hub including a body member having an inner portion provided with a plurality of annularly disposed recesses, said member also being shaped to provide a plurality of channels, each channel extending outwardly from one of said recesses, spoke members having portions inwardly extending through said channels and terminally seated in said recesses, and resilient means carried by the hub adjacent its periphery yieldingly to resist distortion of said spoke members.
2. In a wheel hub, the combination of a body member and a cover plate therefor, the member having an inner portion provided with a plurality of annularly disposed recesses, a plurality of compartments adjacent the periphery of said member, a plurality of radially extending constricted channels formed on said member, each channel connecting a recess with a compartment, complementary pairs of opposingly bowed spring-spokes, each spoke pair having hub portions inwardly extending through a compartment and connective channel to a recess and terminally shaped to be retentively seated in the recess, and resilient means in each compartment yieldingly to resist distortion of said spoke inner portions.
3. In a wheel hub, the combination of a body member and a cover plate therefor, the member having a plurality of annularly disposed recesses in its inner portion, a plurality of compartments adjacent the periphery of said member, a plurality of radially extending constricted channels formed on said member, each channel connecting a recess with a compartment, spring-spokes having bowed portions and straight hub portions, said spokes being arranged in complementary pairs having the bowed portions opposingly disposed and the straight hub portions in adjacent parallelism, each pair of spokes having the bowed portions outwardly extending beyond the hub member, and the straight portions extending through a compartment and connective channel to a recess, means to secure the inner end portions of each spoke pair in a recess, and resilient means in each compartment tending to retain the straight portions of a spoke pair in normal adjacent parallelism.
4. A wheel hub including a body member provided with a plurality of annularly disposed recesses, a plurality of complementary pairs of opposingly bowed spring-spokes, each pair having hub portions terminally secured in one of said recesses, the inner terminal portion of one of each complementary spoke pair being shaped to provide a solid head, the terminal portion of its complementary spoke being shaped to embrace said head, said terminally embraced head of each pair being shaped to be retentively seated in one of said recesses, and means to maintain the hub portions of the spokes in annularly spaced paired relation.
5. A wheel hub including a body member having an inner portion with a plurality of annularly disposed recesses, a channel outwardly extending from each recess, spokes

- terminally seated in said recesses and extending outwardly through said channels, and an annular cover plate adapted to be secured to said hub member, the portions 5 of the member and plate adjacent said spokes being outwardly tapered whereby the outer hub portions of the spokes are normally out of contact with said member and plate.
- 10 6. A wheel hub including a hub plate and a cover plate therefor, the hub plate having a thickened inner portion provided with a plurality of recesses, ribs formed on the hub plate and outwardly extending in spaced 15 paired relation from each recess, means to secure the cover plate to the hub plate, members formed on the hub plate in an annularly spaced relation adjacent the hub plate periphery and axially projecting 20 therefrom to abut against the cover plate, and complementary pairs of spring spokes, each pair having hub portions inwardly extending between adjacent spaced members and between spaced ribs and terminally 25 seated in one of said recesses.
7. A wheel hub including a hub plate, and a cover plate therefor, and means to secure the cover plate to the hub plate, the hub plate having an inner thickened portion 30 to provide a plurality of annularly disposed recesses, a plurality of annularly spaced compartments on said hub plate adjacent the periphery thereof, a channel on the hub plate connecting each recess with a compartment, a plurality of axially projecting 35 members annularly disposed adjacent the periphery of one of said plates and adapted to abut against the other plate, said members being disposed between said annularly spaced compartments and complementary 40 pairs of spring spokes, each pair having hub portions inwardly extending through a compartment and connective channel to a recess and terminally seated in the recess, and resilient means in each compartment 45 yieldingly to resist distortion of said hub portions.
8. In a wheel hub, the combination of a body member, said member having an inner portion provided with a plurality of 50 annularly disposed recesses, said member having a plurality of compartments adjacent the periphery thereof, a plurality of radially extending constricted channels formed on said member, each channel connecting a recess with a compartment, complementary pairs of opposingly bowed spring-spokes, each spoke pair having hub portions inwardly extending through a compartment and connective channel to a 55 recess and terminally shaped to be retentively seated in the recess, and resilient means in each compartment yieldingly to resist distortion of said spoke inner portions.
- 60 In witness whereof, I have hereunto set my hand this 23 day of November, 1920.
- ADELBERT F. KELLY.
